UNITED STATES PATENT OFFICE.

JOHN C. JONES, OF TUCUMCARI, TERRITORY OF NEW MEXICO.

OIL-CONDUCTOR.

No. 796,219.

Specification of Letters Patent.

Patented Aug. 1, 1905.

Application filed January 10, 1905. Serial No. 240,410.

To all whom it may concern:

Be it known that I, JOHN C. JONES, a citizen of the United States, and a resident of Tucumcari, in the county of Quay and Territory of New Mexico, have invented a new and useful Improvement in Oil-Conductors, of which the following is a specification.

My invention relates to feed devices for oil-conveying tubes, and the object is to provide a device that will insure an even and steady flow of oil through a pipe leading from a lubricator to a chamber subject to variations in pressure--such, for instance, as the steam-chest of a locomotive or engine, in which the changes of pressure are not only frequent and constant, but often very great. Experience has proved that in cases of this kind the predominance of pressure first at one end of the conveying-tube and then at the other causes the oil to be delivered to the slide-valve in a most irregular and unsatisfactory manner, supplying too much at one stroke and little or none at all at another, and therefore giving only poor results even when an excessive amount of oil is used. With my device this objectionable irregularity in the delivery of the oil is effectively overcome, thereby insuring the most satisfactory lubrication with a minimum expenditure of oil.

The invention consists in certain novel features and parts and combinations of the same, as will be fully described in the appended specification and then pointed out in the claims, reference being had to the accompanying drawings, in which—

Figure 1 shows a side elevation of my improved oil-conductor in half-section and arranged in operative position in an oil-tube, said tube being shown in section. Fig. 2 shows a central vertical section of my device, taken on line 2 2 of Fig. 1; Fig. 3 is a plan view of the upper end of my improvement; and Fig. 4 is a diagrammatic view of a locomotive-boiler and steam-chest, showing a lubricator connected with the steam-chest by an ordinary feed-pipe, said pipe being provided with my improved oil-conductor.

Broadly speaking, my invention consists of a body introduced in a pipe-line to form one or more oil-chambers therein to arrest the oil in its passage, said chambers being open at the top for the inflow of oil and having outlets therefor at their bottoms, the device having also a central passage-way for oil and steam.

In the drawings I have shown a body adapt-

ed to be introduced in a pipe-line, dividing the same into two compartments, said body having a longitudinal passage-way therethrough and also oil and steam ports leading, respectively, from above and below said partition into said passage-way.

The letter A indicates my device as a whole, which consists principally of the central plate 1, the upper tubular extension 2, and the lower tubular extension 3. The valve 4 at the upper end of the tubular extension 2 and the securing-pin 5 for holding said valve in operative position constitute the remaining parts of my device. The plate 1 and the tubular portions 2 and 3 are preferably formed integral with each other. The longitudinal central bore 6 extends from the top of the device down to a point near the lower end thereof. This bore is provided with the enlarged portion 6^a at its upper end, which forms a chamber for the valve 4. The oil-port holes 7 7 extend downwardly and inwardly at a sharp angle from the exterior of the upper tubular portion 2 into the central bore or chamber 6, (see Fig. 1,) while the steam-port holes 8 8, Fig. 2, extend upwardly and inwardly at a similar angle from the exterior of the lower tubular portion 3 into said chamber 6 and are considerably larger than the oil-port holes 7 7. The lower tubular extension 3 tapers downwardly from the plate 1 to a point near its lower end and terminates in a portion which flares first outwardly to produce a face in the form of a truncated cone and then inwardly to a point, thereby forming the extreme lower end of the device into a cone 9. The diameter of this conical portion is less than the diameter of the upper end of the tubular extension 3. The diminutive oil-outlet holes 10 10 are located at the lower end of the tubular portion 3 at its narrowest part or neck immediately above the truncated conical face. These holes preferably extend downwardly and inwardly and communicate with the central chamber 6 at its lower end.

The valve 4 is provided with a top flange or cap portion 4^a, which normally rests upon the top of the tubular portion 2 to close the upper end of the central chamber of the device. The valve is further provided with an annular groove 4^b, which provides space for the transverse passage of the securing-pin 5, Fig. 3, which passes through suitable apertures in alignment with each other in the wall of the tubular portion 2 at one side of the cen-

ter thereof, Fig. 3. This pin permits the valve to move up and down freely and to rotate, but prevents it from being moved too far from its seat.

In use my device is placed in an oil-pipe B, at one of the joints thereof, with the central flange 1 serving as a gasket for the joint, as illustrated in Fig. 1. When thus inserted, the part of the oil-pipe containing the device is practically divided thereby into two compartments, an upper and a lower, (designated by the letters B' and B².) The external diameter of the tubular portion of the device is smaller than the internal diameter of the oil-pipe B to provide a space between the two.

The operation is as follows: The oil passes down the upper compartment B' of the oil-pipe till it reaches the flange 1, and then through the oil-ports 7 into the central bore or chamber 6, and finally out through the openings 10 to fall in drops from the point of the cone 9. Since the valve 4 seats downward, it is apparent it will prevent oil entering the device save through the ports 7. When the pressure is increased in the lower compartment B² of the oil-pipe, the air or steam in rushing upwardly toward the compartment B' will find its line of least resistance leading through the comparatively large steam-ports 8 into the upper part of the central bore 6 and out past the valve 4, thus leaving the oil-outlets 10 and the oil-ports 7 practically as undisturbed under ordinary changes as if they were valved against the upward passage of fluid. The same is true of the oil accumulated in the lower portion 6^b of the central bore or chamber 6, and also that which shall have accumulated in the chamber B', that forms the lower end of the compartment B' between the upper tubular section 2 and the surrounding section of the oil-pipe. As soon as equilibrium is restored in the upper portion of the pipe the valve 4 closes by gravity and the oil accumulated in the upper or external chamber B' and the lower or internal chamber 6^b flows on by gravity, as usual. If the pressure be reduced in the lower compartment B² of the oil-pipe, this will accelerate the downward flow of oil, as is apparent. If the excess of pressure in the lower compartments suddenly becomes very great, causing a sudden and forcible up-rush of steam, the cone 9 will deflect the steam outwardly and prevent it from directly striking the oil-outlets 10, and since the cone is smaller in diameter than the upper part of the lower tubular portion 3 the steam will not be deflected sufficiently to prevent it from easily striking and entering the steam-ports 8 without changing its general course.

My device also accelerates the downward movement of the lubricator in the oil-pipe by reason of the fact that when drops fall from the point of the cone 9 they descend far more rapidly than if they were trickling

down the walls of the pipe toward their final destination.

That portion of my device below the flange 1 might be cut away and I would still have an effective device, or the upper portion might be removed and the same would be true if the lower part were left; but I prefer to use the device complete, as shown.

When it is desired to thoroughly clean my device, all that is necessary is to bring the upper end of the oil-tube into communication with the outer air by a cock or other suitable means and then turn a current of steam upwardly through the device.

From the foregoing it will be seen that my invention is specially desirable for high-pressure locomotives, since when they are worked at full throttle the back pressure from the steam-chest is so great that it causes the lubricator to feed imperfectly. Again, the oil that has been already fed into the feed-pipe will not flow against this excessive back pressure, even when ordinary feed devices are used, but will be checked in the pipe behind these devices.

With my device a constant flow of oil is secured regardless of the back pressure, the lubricator working perfectly and continuously and the oil being conducted to the valves as fast as the lubricator discharges it.

Having thus described my invention, what I claim as new, and desire to secure by Letters Patent, is—

1. An oil-conductor for a pipe-line comprising a transverse partition adapted to be secured in the pipe-line to divide the same into two compartments, and said partition having a downwardly-extending tubular portion of less diameter than the diameter of the pipe with which the conductor is to be used, the longitudinal bore of the latter extending nearly to the bottom thereof and having a reduced opening leading outwardly therefrom at a point near the lower end of the tubular portion to form an oil-outlet, the conductor being also provided with an oil-port and a steam-port, both extending outwardly from said bore at points above the oil-outlet, the steam-port bringing said bore into communication with the part of the conductor below the partition and the oil-port bringing it into communication with the part above said partition.

2. An oil-conductor for a pipe-line comprising a transverse partition adapted to be secured in the pipe-line to divide the same into two compartments, and having an upwardly-extending tubular portion of less diameter than the internal diameter of the pipe with which the conductor is to be used, said portion having an opening leading from the inner side of the tube outwardly through the same at a point above the dividing-partition and another opening leading outwardly to a point below said partition.

3. An oil-conductor for a pipe-line comprising a transverse partition adapted to be secured in the pipe-line to divide the same into two compartments; and having an upwardly-extending stem of less diameter than the internal diameter of the pipe with which the conductor is to be used, said conductor being provided with a longitudinal bore or chamber having a small outlet at its lower end for the escape of oil below said partition, the conductor further having an oil-port leading from a point in its central bore above said oil-outlet and extending outwardly through the wall of said stem opening at a point above said partition, and a steam-port leading outwardly from said central bore at a point also above said oil-outlet and opening at a point below said partition, said steam-port being larger than said oil-port.

4. An oil-conductor for a pipe-line comprising a transverse partition adapted to be secured in the pipe-line to divide the same into two compartments, and having an upwardly-extending stem of less diameter than the internal diameter of the pipe with which the conductor is to be used, the conductor being provided with a longitudinal bore forming an internal chamber therein and a valve at the upper end of the bore for normally closing the same, said valve opening upwardly, the central bore or chamber having a small oil-outlet at its lower end, opening below said partition, the conductor further having two ports, one for oil and the other for steam, both located above the oil-outlet, and leading from the outside of the conductor to the longitudinal bore therein, the oil-port leading in from a point above, and the steam-port from a point below, the transverse partition, the oil-port being larger than the oil-outlet and the steam-port being largest of all.

5. An oil-conductor for a pipe-line comprising a transverse partition adapted to be secured in the pipe-line to divide the same into two compartments, and having a stem extending upwardly and downwardly from said partition and of less diameter than the diameter of the pipe with which the conductor is to be used, said conductor being provided with a longitudinal bore forming an internal chamber extending from the top of the conductor downwardly nearly through the lower end thereof, and provided at its lower end with a small upwardly and outwardly extending opening for the escape of oil, said conductor being also provided at a point above said oil-outlet with an oil-inlet port leading inwardly and downwardly from a point above said partition and a steam-port leading upwardly and inwardly into said internal chamber from a point below said partition, the oil-inlet port being larger than the oil-outlet and the steam-port being largest of all.

6. An oil-conductor for a pipe-line comprising a circular plate adapted to be secured in

the pipe-line at a joint therein, a stem portion at the center of said plate extending above and below the same, said conductor having a central bore extending from its top nearly through the lower end thereof, a valve at the upper end of said bore normally closing the same and opening upwardly, the bore being enlarged at its upper end for the reception of the valve the portion of the conductor extending downwardly from the circular plate, tapering from the plate to a point near its lower end then flaring outwardly to form a truncated conical face and then tapering rapidly inward from all sides to form a blunt cone-shaped point, the conductor being provided immediately above said truncated conical face with a diminutive opening extending downwardly and inwardly from the outside of the stem to the lower end of the bore therein to form an outlet for the oil, the conductor having an oil-port leading downwardly and inwardly at a sharp angle from a point on the outer periphery of the conductor immediately above said circular plate into said internal bore and also a steam-port extending upwardly and inwardly at a sharp angle from a point on the outer periphery of the conductor immediately below said circular plate into said internal bore, the oil-port being larger than the oil-outlet and the steam-port being larger than either of the others, and the diameter of the inverted cone at the lower end of the conductor being less than the diameter of the stem at the outer ends of the steam-ports.

7. The combination with an oil-delivery tube of an oil-conductor, comprising a circular plate, with a stem portion at the center of the plate extending above and below the same, the conductor being adapted to be received into the pipe at a joint thereof dividing the pipe into upper and lower compartments, the plate forming a gasket for the joint, the stem portion of the conductor being of less diameter than the internal diameter of the pipe and extending central and longitudinal thereof, the conductor being provided with a central longitudinal bore extending from the top thereof to a point near the lower end, a valve at the upper end of said bore normally closing the same and opening upwardly, the lower portion of the conductor extending downwardly from the circular plate, tapering from the plate to a point near its lower end, then flaring outwardly to form a truncated conical face, and then tapering rapidly inward from all sides to form a blunt cone-shaped point, the conductor being provided immediately above said truncated conical face with diminutive openings diametrically opposite each other and extending downwardly and inwardly from the outside of the stem to the lower end of the bore therein to form oil-outlets, said central bore having diametrically opposite oil-ports extending outwardly and upwardly at a sharp angle and opening in the upper compartment of the pipe.

line, and also having diametrically opposite steam-ports extending downwardly and outwardly at a similar angle to establish communication between said central bore and the lower compartment of the pipe-line, the plane of the steam-ports being preferably at a right angle to the plane of the oil-ports, the inner ends of the steam-ports being above the inner

ends of the oil-ports, the steam-ports being larger than the oil-ports and the oil-outlets being the smallest of all.
